UNITED STATES PATENT OFFICE

2,338,963

ADJUSTABLE HONE

John J. Palotce, Youngstown, Ohio

Application March 25, 1943, Serial No. 480,539

4 Claims. (Cl. 51—184.3)

This invention relates to adjustable abrasive hones, the present invention being an improvement upon the hones disclosed in my U. S. Letters Patent No. 2,269,378 dated January 6, 1942, and in my copending application Serial No. 469,714 filed December 21, 1942.

In my aforesaid patent and application an adjustable abrasive cylindrical or tapered stone hone was disclosed having a relatively small diameter, said hones being particularly adapted for grinding, machining, finishing, polishing, or boring, cylindrical bearings of relatively small diameter, such as crank-shaft bearings, connecting-rod bearings, wrist pin bearings, main bearings, or the like. Said hones each consisted of a spindle carrying an annular series of radially shiftable segmental stone holders each carrying a carborundum hone section, said holders and hones when fully contracted around the spindle forming an unbroken cylindrical or tapered grinding surface having spiral grooves on its exterior grinding surface. The said holders and spindle were provided with complementary tapered surfaces, means being provided for shifting the spindle axially of the holders to effect an expansion or contraction of the hone with respect to the spindle to vary the actual diameter of the hone, said hone having means for yieldably maintaining the tapered surfaces of the holders and spindle in close contact while permitting shifting of the spindle. Said hones were also provided with indicator scales for visibly indicating the diameter to which the hones were adjusted.

One object of my present invention is to provide an improved hone of the above type for grinding relatively large bores, in which the hone segments when in half open position, are ground to cylindrical shape allowing an adjustment of diameter above and below such position; said hone having a relatively large number of hone segments presenting a larger number of honing surfaces at a large number of points around the hone, my present arrangement permitting use of as many blades as desired.

Another object of the invention is to provide a hone of the above type in which the blades may be disposed parallel with the axis of the hone, or may be disposed at an angle thereto which latter arrangement imparts better cutting facility thereto, as often a blade disposed in parallel relation will merely rub instead of grind or polish.

A further object of the invention is to provide a hone of the above type in which the stone blades may be replaceably held in the holders so that different sets of blades of different grits may

be used in the same holders, and new stones may be inserted in place of worn stones in the same holders.

5 A still further object of the invention is to provide an adjustable hone of the above type having an anti-friction bearing disposed between one end of the series of blades and the diameter adjusting nut thereby permitting easy turning of the nut and reducing friction and wear on the tapered 10 ends of the holders adjacent the nut, and more accurate adjustment of the hone, especially for larger hones, and also permitting use of a stiffer spring in the assembly.

Other minor objects of the invention will be 15 hereinafter set forth.

I will explain the invention with reference to the accompanying drawings which illustrate various practical embodiments thereof to enable others familiar with the art to adopt and use the 20 same; and will summarize in the claims, the novel features of construction, and novel combinations of parts, for which protection is desired.

In said drawings:

Fig. 1 is a longitudinal section through one 25 form of adjustable stone hone embodying my invention.

Fig. 2 is a partial transverse section through one form of my novel hone taken on the line 2—2, Fig. 1, showing the stones cast in the 30 holders and showing the undercut stone holding grooves formed in the outer faces of the holders.

Fig. 3 is a partial transverse section, similar to Fig. 2, showing in a modified hone the hones cast in the holders and the grooves disposed at the 35 center of the outer faces of the blades.

Fig. 4 is a partial transverse section, similar to Fig. 2, taken through a still modified hone, showing the stones cast in the holders, and showing the blades having straight sides.

40 Fig. 5 is a partial transverse section, similar to Fig. 2, taken through a still modified hone in which the stones are cemented to the holders and the blades having straight sides.

Fig. 6 is a partial transverse section, similar to Fig. 2, taken through a still modified hone, showing the stones cast into metallic bases, and the bases removably mounted in the holders.

Fig. 7 is a partial transverse section, similar to Fig. 2, taken through a still further modified hone, showing the stones cemented into metallic bases, and the bases removably mounted in the 50 holders.

Fig. 8 is an enlarged top plan view of a holder 55 shown in Figs. 6 and 7, detached.

Fig. 9 is a side elevation of the holder shown in Fig. 8.

Fig. 10 is a side elevation of a stone cemented or cast into a metallic base as shown in Figs. 6 or 7.

Fig. 11 is an end elevation of the stone and metallic base shown in Figs. 6 or 7.

Fig. 12 is a reduced side elevation of the hone assembly having both oppositely extending peripheral grooves in its periphery.

Fig. 13 is an end elevation of the assembly shown in Fig. 12.

Fig. 14 is a side elevation similar to Fig. 12 but showing the assembly provided with parallel longitudinal grooves.

Fig. 15 is an enlarged detail section.

Fig. 16 is a side elevation of a modified hone assembly having the stones and holders disposed at an angle to the axis of the hone.

Fig. 17 is a transverse section on the line 17—17, Fig. 16.

Fig. 18 is an enlarged plan view of a stone holder used in the hone shown in Fig. 16.

Fig. 19 is a side elevation of the holder shown in Fig. 18.

Fig. 20 is a bottom plan view of the holder shown in Fig. 18.

Fig. 21 is an end view of the holder shown in Fig. 18.

As shown my novel hone preferably comprises a relatively long tubular pilot spindle 1 of relatively large diameter and of somewhat greater length than the desired abrasive surface. Upon spindle 1 adjacent opposite ends thereof are rings 2, 2a, having spaced series of circumferentially disposed enlargements 3 each having longitudinally disposed slots 4 therein provided with tapered bottom walls 5, the walls 5 sloping at the same angle and in the same direction in the rings 2—2a, and the slots in the rings 2—2a being longitudinally aligned. Preferably each ring 2 is welded or shrunk fit upon spindle 1.

Beyond the ring 2a, tubular spindle 1 is externally threaded as at 1a to receive the threaded bore 6a in the hub of a hand wheel 6 having a knurled peripheral wall 6b and having a web 6c. In the outer wall 6b of wheel 6 are a series of holes 6d adapted to receive, if necessary, a tool to effect rotation of wheel 6 on spindle 1. Within the adjacent end of spindle 1 is a head 7 having a peripheral flange 7a welded, riveted or bolted in place therein, said head having an axially disposed bore 7b internally threaded as at 7c to receive the threaded shank 8a of a handle 8 of non-circular cross-section whereby the spindle 1 may be held against rotation when rotating hand wheel 6.

In the opposite end of tubular pilot spindle 1 is a tubular member 9 making a sliding fit therein, member 9 being of substantial length and having an outer head 10 carrying an internal axially disposed cylindrical portion 11. The inner end of member 9 is closed by a wall 12 having a central hole 12a for the passage of a bolt 13 having its outer end threaded into a fixed head 14 mounted by rivets, bolts or welding within the spindle 1 as shown in Fig. 1. Bolt 13 is provided with an enlarged head 13a slidably disposed within cylindrical portion 11 of member 9. A spring 15 is disposed around bolt 13 between head 13a and wall 12 normally tending to draw member 9 inwardly of the spindle 1 but yieldably permitting the member 9 to be shifted outwardly thereof against the compression of spring 15. The inner end of spring 15 is centered on wall 75

12 by means of a centering cup 16 of light metal or the like having an axial hole through which bolt 13 passes. Mounted upon the outer end of member 9 is an annular conical flange 17 for the purpose hereinafter described. In the outer end of head 13a of bolt 13 is a diametrical slot 13c for engagement with a screw driver or other tool whereby bolt 13 may be threaded into fixed head 14.

10 The pairs of aligned slots 4 of the enlargements 3 of rings 2—2a on spindle 1 are adapted to slidably support a plurality of metallic blade holders 18, said holders extending substantially the full length of the spindle and beyond said rings 2—2a, said holders 18 being mounted as an annular series around the spindle 1 and being of such individual width that the sides thereof will substantially abut when the holders 18 are fully retracted (Figs. 2, 3, 4 and 6). Each holder 18 is provided with a recess holding therein an abrasive stone 19 of carborundum or other honing material which may be cast or cemented or removably held in the related holder; said hones 19 extending radially outwardly beyond the outer faces of the holders 18 and having arcuate outer peripheries whereby the peripheries of all the hones 19 when their holders 18 are in approximately half-opened position will together form a cylindrical grinding surface. In the form shown in the drawings 18 such holders and hones are provided in the assembly, but a greater or lesser number may be used.

Figs. 2 to 7 and 15 show various types of stone blades 19 and holders 18 which may be used. In Fig. 2, the holders 18 have undercut recesses 18a in their outer edges 18b and at their centers 18a into which the carborundum hones 19 are cast. In Fig. 3 a similar construction is shown in which the edge recesses 18b are omitted. The holders 18 of Figs. 2 and 3 have radially disposed side walls 18c which are adapted to substantially abut the side walls of adjacent holders when the blades are fully contracted, and the side walls 19a of hones 19 form continuations of the side walls 18c of the holders. In Fig. 4 the holders 18 have parallel side walls 18d but the hones 19 are otherwise of same general shape and cast into the recesses 18a of holders 18 in the same manner as above described in connection with Fig. 3, the side walls 19a of the hones extending beyond the side walls of 18d of the holders. In Fig. 5 the recesses 18e in the holders 18 are straight-sided and receive correspondingly-shaped ribs 19e on the hones 19 which are cemented into place therein, the side walls 19b of the hones forming continuations of the parallel walls 18d of the holders 18.

In Fig. 6 the holders 18 are similar to those shown in Fig. 4 and provided with central undercut recesses 18a; but the hones 19 are cast into metallic base plates 20 conforming in size and shape with the general shape of the outer faces of the holders 18 and having undercut projections 20f fitting the undercut recesses 18a, the plates 20 with the hones 19 cast therein being then slipped endwise into place in the blades 18 and held therein by set screws 21 (Fig. 15) tapped through the sides of the holders 19 and adapted to press upon the inclined side walls of the undercut portions 20f of base plates 20, thereby forcing the plates 20 and their hones 19 downwardly into position in the holders 18 for accurate honing. In Fig. 7 a similar arrangement is shown involving a modified type of holder 18 and hone 19, the hone being cemented rather than cast

into the metallic base plate 20. The type of hone and holder shown in Figs. 6, 7 and 15 which utilizes a base plate 20 pressed from sheet steel or similar metal, permits provision of renewal of hones 19, or interchangeability of said hones, so that hones 19 of various different grades or grits may be used with the same holders 18, coarser hones 19 being used for cutting, finer hones for polishing motor cylinders, and very fine grit hones for honing soft metal such as bearings.

On the underside of each holder 18 is a rib 18h having spaced tapered inner edge portions 18k conforming with the taper 5 of the bottom walls of slots 4 of the spindle enlargements 3, said ribs 18h slidably fitting the slots 4, the walls thereof serving as guides for the holders, whereby each of the holders 18 when shifted axially of the spindle 1 may be moved radially inwardly or outwardly thereof, but are at all times prevented from lateral movement thereof. Each of the tapered surfaces 18k are of greater length than their corresponding tapered surfaces 5 of enlargements 3.

At each end of each holder 18 is a projecting lug 18m tapered on its upper face as at 18n, one end entering and directly engaging the conical head 17 carried by the slideable member 9, as shown in Fig. 1. Engaging the other tapered end 18n of each holder 18 is an antifriction bearing 22 (Fig. 1) having one race 22a beveled to conform with the taper 18n of the holder 18 and engaging same directly. The other race 22b of the anti-friction bearing has its outer face seated in an annular recess 6x in the adjacent face of hand wheel 6, and is centered thereby, so that as hand wheel 6 is rotated the bearing 22 permits easy turning of said wheel and more accurate adjustment of the hone, which is a very desirable feature especially for large diameter hones, since the bearing 22 also permits the use of a stiffer spring 15 while reducing friction and wear on the tapered surfaces 18n.

By the above construction the ends of the holders 18 are maintained upon the spindle 1, the same being confined between the head 17 and the race 22a of bearing 22. The distance between the head 17 and race 22 however is variable, owing to the provision of spring 15 interposed between the fixed bolt head 13a and the inner wall 12 of tube 9, and thus the conical holder engaging faces of the head 17 and outer race 22a are permitted to engage the correspondingly shaped ends 18n of the holders 18 in all retracted or projected positions of the holders 18 to thereby yieldably maintain the tapered surfaces 18k of the holders 18 in close contact with their corresponding tapered surfaces 5 of spindle 1 for any axially adjusted position of spindle 1 with respect to the holders 18.

When the parts are assembled the hone may be placed in a power grinding machine and the peripheries of all of the hones 19 when in partly or half open position shown in Fig. 1, ground accurately to form a truly cylindrical surface concentric with the axis of the spindle, thereby allowing adjustment of the diameter of the hone above and below this half opened position at which the stones are ground cylindrical. The 18 hones 19 may be varied in number, a larger number resulting in more honing surface at a greater number of points around the bores being ground.

As shown in Fig. 12 the peripheries of the hones 19 may be provided with grooves 25 extending in opposite directions which, when the

holders are fully retracted, form interconnecting spiral grooves defining diamond-faced cutting faces providing recesses which will permit accumulations of cuttings and grindings to pass off to one side, which cuttings if not removed might build up the effective diameter of the hone and throw same off-center; or the stones 19 may be provided with longitudinally extending grooves 26 (Fig. 14) running lengthwise of the hones 19.

As shown in Figs. 12 and 14, means are provided for visually indicating to the operator the diameter to which the hone is adjusted. The periphery of wheel 6 adjacent the end of hone section 19 is provided with an annular series of graduations 27 cooperating with any of the edges of the hone sections so that when the wheel 6 is rotated relative to the spindle 1 the graduations will directly indicate the change in diameter of the hone without necessitating the use of calipers or other extraneous measuring instruments.

In Figs. 16 to 21 a modified adjustable hone is illustrated which is in general similar to those disclosed in Figs. 1 to 15, but instead of the stones 19 being disposed parallel with the axis of the hone or spindle 1 the holders are arranged helically, that is, in such manner that the rib 18h on the underside of each holder extends diagonally of the holder, from a point adjacent one edge thereof at one end to a point adjacent the opposite edge thereof at the other end, as indicated in Figs. 18 to 20. By this construction the axis of the holders 18 and the hones 19 carried thereby when mounted on the spindle assume an angularity with respect to the axis of the spindle 1 as shown in Fig. 16. Ribs 18h on the holders 18 however being slideable in the axially aligned pairs of slots 4 in the enlargements 3 of the pair of rings 2-2a and thus move axially with respect to the axis of the spindle. Such diagonal arrangement of the blades 19 causes the same to be set at a cutting angle to the work, whereas the blades when disposed parallel with the axis of the spindle in some instances merely rub the work rather than grind or polish same. The diagonal arrangement of the blades 19 in Figs. 16-21 furthermore results in smoother and faster grinding, cutting or polishing. The hone shown in Figs. 16 to 21 otherwise operates in the same manner as the modifications shown in Figs. 1 to 15. Aside from the angularity of the ribs 18h, holders are or may be identical with those shown in the preceding figures and the hones 19 may be cast or cemented therein, or may be cast or cemented into metallic base plates 20, such as shown in Figs. 6 and 7, the base plates 20 with the hones 19 cemented or cast therein being held in the undercut grooves 18a in the outer faces of the holders 18 by means of set screws 21 such as shown in Fig. 15.

I do not limit my invention to the exact forms shown in the drawings, for obviously changes may be made therein within the scope of the claims.

65 I claim:

1. An adjustable hone, comprising a relatively large hollow spindle; spaced series of enlargements on said spindle inset from the ends thereof, said enlargements having axially aligned slots 70 therein provided with inclined bottom walls sloping in the same direction; a plurality of longitudinally disposed stone holders around the spindle embracing the enlargements and having ribs on their undersides provided with correspondingly inclined inner edges seating upon the inclined

bottoms of the slots; segmental stones in the respective holders; extensions at the ends of the holders having opposed faces respectively inclined towards the spindle; a hand-wheel axially movably mounted on the spindle adjacent one end and having an inclined bearing portion engaging the inclined faces of the extensions at the adjacent end of the holders; a conical member yieldably mounted adjacent the opposite end of the spindle and having an inclined bearing portion engaging the inclined faces of the extensions at said end of the holders; said holders having undercut grooves in their outer faces; and said stones being fixedly secured therein.

2. An adjustable hone, comprising a relatively large hollow spindle; spaced series of enlargements on said spindle inset from the ends thereof, said enlargements having axially aligned slots therein provided with inclined bottom walls sloping in the same direction; a plurality of longitudinally disposed stone holders around the spindle embracing the enlargements and having ribs on their undersides provided with correspondingly inclined inner edges seating upon the inclined bottoms of the slots; segmental stones in the respective holders; extensions at the ends of the holders having opposed faces respectively inclined towards the spindle; a hand-wheel axially movably mounted on the spindle adjacent one end and having an inclined bearing portion engaging the inclined faces of the extensions at the adjacent end of the holders; a conical member yieldably mounted adjacent the opposite end of the spindle and having an inclined bearing portion engaging the inclined faces of the extensions at said end of the holders; said holders having undercut grooves in their outer faces; hone base plates on said holders having corresponding undercut ribs filling the said grooves, said stones being fixedly mounted in said base plates; and means extending through the sides of the holders and engaging the sides of the undercut ribs of the base plates for locking the base plates in the holders while urging the base plates downwardly upon the holders.

3. An adjustable hone, comprising a relatively

large hollow spindle; spaced series of enlargements on said spindle inset from the ends thereof, said enlargements having axially aligned slots therein provided with inclined bottom walls sloping in the same direction; a plurality of longitudinally disposed stone holders around the spindle embracing the enlargements and having ribs on their undersides provided with correspondingly inclined inner edges seating upon the inclined bottoms of the slots; segmental stones in the respective holders; extensions at the ends of the holders having opposed faces respectively inclined towards the spindle; a hand-wheel axially movably mounted on the spindle adjacent one end and having an inclined bearing portion engaging the inclined faces of the extensions at the adjacent end of the holders; a conical member yieldably mounted adjacent the opposite end of the spindle and having an inclined bearing portion engaging the inclined faces of the extensions at said end of the holders; an antifriction bearing having a race carried by the wheel and having a second race provided with a conical face engaging the inclined faces of the extensions at the adjacent end of the holders.

4. In an adjustable hone, having a spindle provided with spaced series of enlargements thereon, having axially aligned slots therein provided with inclined bottom walls sloping in the same direction; a plurality of longitudinally disposed stone holders maintained around the spindle having ribs on their undersides provided with correspondingly inclined inner edges seating upon the inclined bottoms of the slots; extensions at the ends of the holders having upper faces inclined towards the spindle; a hand-wheel axially movably mounted on the spindle adjacent one end; an anti-friction bearing having a race carried by the wheel and having a second race tapered and engaging the inclined faces of the extensions at the adjacent end of the holders; and a conical member yieldably mounted adjacent the opposite end of the spindle and engaging the inclined faces of the extensions at the said end of the holders.
